UNITED STATES PATENT OFFICE.

PAUL SERENE, OF YOUNGSTOWN, OHIO, ASSIGNOR OF ONE-THIRD TO L. F. DONNELL
AND ONE-THIRD TO B. P. HIGBY, BOTH OF YOUNGSTOWN, OHIO.

MANICURE DEVICE.

Application filed March 2, 1922. Serial No. 540,467.

To all whom it may concern:

Be it known that I, PAUL SERENE, a citizen of the United States, and a resident of Youngstown, county of Mahoning, and State 5 of Ohio, have invented a new and useful Improvement in Manicure Devices, of which the following is a specification, the principle of the invention being herein explained and the best mode in which I have contemplated applying that principle, so as to distinguish it from other inventions.

The present invention relates to a manicure device comprising a small thimble in which is mounted means for polishing, 15 cleaning and filing the nail, the whole device being small enough to be readily carried in a pocket or the like, and being so arranged that it may be easily used. The buffing and cleaning means are mounted 20 within the thimble in such a manner that the device automatically adapts itself to fingers of different sizes and the whole device is conveniently and readily assembled. To the accomplishment of the foregoing and 25 related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

35 Fig. 1 is a vertical longitudinal section through the thimble taken on the line 1—1 of Figs. 1 and 3 and looking in the direction away from the cleaning device; Fig. 2 is a central horizontal section on the line 2—2 40 of Fig. 1; Fig. 3 is a section on the line 3—3 of Fig. 2; and Fig. 4 is a sectional view of the detail showing the cleaning device taken on the line 4—4 of Fig. 3.

The present device consists of an outer 45 casing or thimble 2 which is provided on the inside, as shown in Fig. 1, with a curved plate 3 having a down-turned flange 4 around its edges, this plate being attached to the inner surface of the thimble by means 50 of two flat springs 5 which are riveted as at 6 to the plate and to the thimble. This plate is provided within the flanges with a buffing pad 7 which is thicker than the

flanges in the plate, and is of the usual construction for the buffing of finger nails, and 55 is preferably covered with chamois.

At one side of the plate there is mounted a cleaning and filing device which consists of a spring 8 pinned or riveted to the plate 3, the forward end of the spring being 60 curved down within the thimble and backward toward the open end of the thimble, and this end of the spring is provided with a file and cleaner consisting of an arcuate member 9 having at its center a pointed end 65 10 with a fairly sharp upper edge 11 adapted to enter under the nail to clean the same, and this arcuate member is also provided with a groove 12 to receive the outer edge of the nail, the groove being provided with 70 a series of file teeth 13 so as to file the nail as the member is moved back and forth across the same. This same action both cleans and files at one time. As shown, this device is mounted at the right hand edge 75 of the plate looking from the open end of the thimble, and is therefore not used when the nail is being buffed, but is used separately without the buffer having any action.

By means of the spring mounting for the 80 buffer, the open space in the thimble below the buffer will be small enough to enable the buffer to contact a normally small finger, and the buffer can be raised against the action of the spring to receive fingers which 85 are larger, and the space between the plate in its normal position and the top of the thimble is sufficient to allow the device to be used for a normal range of size of fingers. The spring which carries the cleaning and 90 filing member is sufficiently resilient to allow this member to be engaged with the nail so that the cleaning and filing actions may readily take place.

This manicure implement is small enough 95 to be readily carried in a pocket or in a small purse, being less than an inch and one-half long and about an inch in greatest diameter, and the thimble proper will be made of any suitable material such as steel 100 or silver, and if made of steel, it will be nickelplated, or silver or gold-plated, in order to enhance the appearance of the article. The buffer and plate are carried by flat springs which are securely fastened 105 to both the thimble and the plate so that

the parts of the device may be readily assembled and are secured against accidental detachment.

Other modes of applying the principle of my invention may be employed instead of the one explained, change being made as regards the mechanism herein disclosed, provided the means stated by any of the following claims or the equivalent of such 10 stated means be employed.

I therefore particularly point out and distinctly claim as my invention:—

1. In a manicure device, the combination of a thimble, and a curved buffering pad resiliently mounted therein.
2. In a manicure device, the combination of a thimble, a curved buffering pad mounted therein and a resiliently mounted cleaning and filing member below said pad.
3. In a manicure device, the combination

of a thimble, a curved buffering pad resiliently mounted therein and a resiliently mounted cleaning and filing member below said pad.

4. In a manicure device, the combination of a thimble, a curved plate, springs attached to said plate and thimble to resiliently space said plate from the interior of said thimble, and a buffering pad mounted on said plate.

5. In a manicure device, the combination of a thimble, a curved plate, springs attached to said plate and thimble to resiliently space said plate from the interior of said thimble, a buffering pad mounted on said plate, and a curved spring attached to said plate and carrying a nail cleaning and 35 filing member.

Signed by me this 28th day of February, 1922.

PAUL SERENE.
